UNITED STATES PATENT OFFICE.

HENRY H. SANFORD, OF MANSFIELD, OHIO.

GAS HEATER.

Application filed May 29, 1922. Serial No. 564,466.

To all whom it may concern:

Be it known that I, HENRY H. SANFORD, a citizen of the United States, residing at Mansfield, in the county of Richland and State of Ohio, have invented certain new and useful Improvements in Gas Heaters; and I do declare the following to be a full, clear, and exact description of the invention, such as will enable others skilled in the art to which it appertains to make and use the same.

My invention relates to improvements in gas heaters and more particularly to those of the type employing a plurality of incandescent "radians" resting against the front side of a fire back mounted within a suitable casing, one object of the invention being to provide a fire back which is movable upwardly when inserting or removing the "radians", but one which is normally lowered to hold said "radians" in place.

A further aim of the invention is to provide for spacing the fire back from the back and top of the casing to provide an air circulating passage, taking advantage of waste heat which would otherwise radiate rearwardly and upwardly from said fire back, for the purpose of heating air to be discharged from the upper end of the casing.

The invention is designed to be inset in a wall and a hood or visor is employed at the upper end of the casing, to prevent any dust rising with the hot air from soiling the wall above the heater, a further aim being to provide extremely simple, yet highly efficient means for securing the hood or visor detachably in place.

A still further object is to provide for spacing the casing of the heater from vertical and horizontal studs in the wall with which it is inset.

With the foregoing and minor objects in view, the invention resides in the novel subject matter hereinafter described and claimed, the descriptive matter being supplemented by the accompanying drawings.

Figure 1 is a front elevation of a heater constructed in accordance with my invention.

Figure 2 is a vertical transverse sectional view as indicated by line 2-2 of Fig. 1.

Figure 3 is a vertical section on line 3-3

of Fig. 2, looking in the direction of the arrows.

Figure 4 is a horizontal section on line 4-4 of Figs 2 and 3.

Figure 5 is a detail horizontal section as indicated by line 5-5 of Fig. 3.

Figure 6 is a disassembled perspective view showing the visor and the upper portion of the casing in juxtaposition.

Figure 7 is a perspective view illustrating the fire back and its supporting shelf juxtaposed.

Figure 8 is a perspective view showing the fire back in place upon its supporting shelf.

Figure 9 is a perspective view of one of the side plates which extend forwardly from the vertical edges of the fire back to the front of the casing.

In the drawings above briefly described, the numeral 1 designates a rectangular casing which is preferably covered with asbestos or other insulating material, said casing being closed at its upper, lower and vertical sides and at its back, while its front is partially open, being provided with a cast metal front plate 2 which is of a size to extend beyond the sides of the casing, being curved rearwardly at said sides as shown. The upper end of the plate 2 is formed with hot air outlets 3, and the lower portion of said plate is formed with air inlet slots 4, some of which may well be in a supplemental plate 5 detachably secured to the plate 2 over an elongated opening 6 through which access may be had to a suitable burner 7 in the lower portion of the casing. Between the removable plate 5 and the openings 3, plate 2 is formed with a relatively large opening 8 and at the vertical edges of this opening, other openings 9 are preferably formed to permit escape of heat. The plate 2 may be secured to the casing in any preferred manner, preferably by means of bolts 10 and the supplemental plate 5 may be similarly secured to the plate 2. The handle 12 of the gas valve with which the burner 7 is provided, and an adjusting handle 13 for the air mixer 14 of said burner, preferably extend forwardly through certain of the slots 4 or through other openings provided for the purpose.

100

As above stated, the casing is adapted to be inset in a wall and in order to space its bottom and vertical sides from horizontal and vertical studs 15 and 16 respectively, with which the wall is provided, I provide channel-shaped sheet metal spacers 17 having outstanding flanges 18 which are suitably secured to said bottom and vertical sides, being adapted to bear against the studs as shown in Figs. 2, 3 and 4. To prevent any dust rising with the heat from soiling the wall above the heater, an appropriate visor 19 is provided, the rear edge of said visor having a plurality of notches 20 formed therein and integral stirrups 21 extending across said notches below the upper side of the visor. In front of the stirrups 21 the visor 19 is formed with depending lugs 22, each having a reduced end 23 and a downwardly facing shoulder 24. The stirrups 21 are adapted to engage forwardly facing hooks 25 formed on the upper end of the front plate 2, the bills of said hooks being received in the notches 20, while the reduced ends 23 of the lugs 22 are adapted for reception in openings 26 formed in the rearwardly curved upper portion of said plate. This arrangement effectively holds the visor in place, yet by lifting the front edge of said visor and moving the latter forwardly, it may be quickly and easily removed, it being understood that a reversal of this operation is employed when applying said visor.

Extending horizontally across the casing 1 behind the lower edge of the opening 8 and spaced from the back wall of said casing is a horizontal shelf 28 having openings 29 above the several jet openings of the burner 7, whereby to permit flame from this burner to rise into and heat the hollow "radians" 30, which rest upon the shelf between parallel ribs 31 formed on the same. The shelf 28 is preferably formed at each of its ends with a pair of integral studs 32 which as seen in Figs. 3 and 4, extend outwardly through openings in the vertical sides of the casing, whereby to secure said shelf in place. The projecting outer ends of these studs are preferably received in the channel spacers 17 with which the casing sides are provided, so that said spacers will prevent the studs from striking the wall and interfering with proper insertion of the heater into said wall, when first installing the device. At points spaced inwardly from its ends and spaced behind its front edge, shelf 28 is provided with upstanding ears 33 to which a pair of vertical side plates 34 are secured by screws or the like 35, said plates extending forwardly to the vertical edges of the opening 8, which edges are preferably flanged as at 36 to engage the front edges of said plates, as shown in Fig. 4. At their upper ends, the side plates 34 rest in angular seats 37 formed at the inner ends

of bracket plates 38 which are secured to and extend inwardly from the vertical sides of the casing. Either separate from or integral with the vertical side plates 34, is a bottom plate 39 which extends from the front edge of the shelf 28 to the lower edge of the opening 8. The three plates 34 and 39 prevent lateral and downward radiation of heat from the radians 30 and thus insure that this heat shall be thrown forwardly.

The numeral 40 designates a vertically positioned fire back which rests upon the shelf 28 behind the radians 30, said shelf having a rear rib 41 to co-operate with vertical guide flanges 42 on the back of the casing, in holding said fire back against rearward movement. The upper end of the fire back is provided with a forwardly extending flange 43 extending entirely to the plate 2, at the upper edge of the opening 8, while the vertical edges of said fire back are formed with vertical flanges 44 which contact with the plates 34 and shield the latter from a great deal of intense heat which would otherwise be thrown against them by the endmost of the radians 30.

At the juncture of the flange 43 with the fire back 40, a channel 45 is formed throughout the width of said fire back, said channel being adapted to receive lugs 46 which extend upwardly from the radians 30. Attention may here be directed to the fact that whereas it is customary to raise the radians and swing their lower ends forwardly, in order to remove them and to reverse this operation when applying the radians, I do not use this method of securing them in place. The entire fire back 40, although being mounted rigidly, is not secured to any parts and may be readily raised sufficiently to permit the lugs 46 to be inserted into the channel 45 or into a plurality of openings which might be used in place of said channel. Thus, the radians are more effectively held in place and they cannot be accidentally detached, so that danger of breakage is minimized.

In addition to the features above pointed out, attention is directed to the fact that by pushing upwardly upon the flange 43, after removing the radians 30, the front end of the fire back 40 is forced to move forwardly so that it may be easily grasped and removed, it being therefore a very simple matter to gain access to the back of the casing for the purpose of driving screws or the like 47 therethrough to secure the casing to the sheathing of the wall into which it is inset (see Fig. 2). Also, it will be observed that the spacing plates 42 and the side plates 34, hold the fire back 40 in spaced relation with the back and vertical side walls of the casing, leaving free passages through which hot air may travel to be discharged through the openings 3 and 9. This hot air is radi-

ated from the fire back of the burner to some extent and its volume is constituted partly by fresh air entering the openings in the lower portion of the casing and being 5 heated by contact with interior parts.

Particular attention is invited to the novel manner of securing the visor 19 in place; to the construction and mounting of the fire back 40, permitting vertical movement 10 thereof in securing the radiants 30, and to the spacing of the fire back from the casing for the purposes set forth. Also, the manner of mounting the shelf 28, including the studs 32 which extend through the sides of 15 the casing into the protecting and spacing members 17, constitute rather important features.

Since excellent results may be obtained from the exact details disclosed, they are 20 preferably followed. It is to be understood however that within the scope of the invention as claimed, numerous minor changes may be made.

I claim:

25 1. A heater comprising a casing having an opening in its front and provided with a horizontal support extending across its interior, a burner below said support, a fire back resting on said support and free to move upwardly therefrom, and a plurality of radiants resting on said support in front of said fire back, said fire back and radiants being relatively movable and being provided with co-acting means for securing the radiants in 30 place when the fire back is lowered and for releasing said radiants from engagement with the fire back when said fire back is raised.

2. A heater comprising a casing having 40 an opening in its front and provided with a horizontal support extending across its interior, a burner below said support, a fire back resting on said support and free to move upwardly therefrom, and a plurality 45 of radiants resting on said support in front of said fire back, said radiants and fire back

being relatively movable, said radiants having upwardly extending lugs on their upper ends, said fire back being recessed to receive said lugs when lowered and to free said 50 radiants when raised.

3. A heater comprising a casing having an opening in its front and vertical plates extending rearwardly from the vertical edges of said opening adjacent the vertical 55 sides of the casing, a horizontal shelf extending across said casing adjacent the lower edge of said opening, a burner below said shelf, a fire back resting on and rising from the rear portion of said shelf, the back 60 of the casing being provided with means for spacing said fire back therefrom, a horizontal flange integral with and extending forwardly from the upper edge of said fire back to the upper edge of said opening, and vertical flanges extending forwardly from the vertical edges of said fire back at the inner sides of said vertical plates, said shelf and fire back being adapted for holding a 65 plurality of radiants in place 70

4. A device of the class described comprising a casing, a shelf extending horizontally across said casing and having integral studs on its ends extending through the vertical 75 casing sides, and channel-shaped guards secured to the outer faces of said casing sides and receiving the outer ends of said studs.

5. The combination with a heater casing having a rearwardly extending portion 80 overlying its top; of forwardly facing hooks on said rearwardly extending portion, the latter having openings in front of said hooks, a visor notched at its rear edge to receive said hooks and provided with stirrups spanning the notches for engagement with said hooks, and depending lugs on said visor received at their lower ends in said openings.

In testimony whereof I have hereunto set my hand.

HENRY H. SANFORD.
